His Attorney

UNITED STATES PATENT OFFICE.

EDWARD H. BRANSON, OF PITTSFIELD, MASSACHUSETTS, ASSIGNOR TO GENERAL ELECTRIC COMPANY, A CORPORATION OF NEW YORK.

UNIVERSAL DIE.

1,340,006.

Specification of Letters Patent.

Patented May 11, 1920.

Application filed September 3, 1918, Serial No. 252,487. Renewed March 19, 1920. Serial No. 367,123.

To all whom it may concern:

Be it known that I, EDWARD H. BRANSON, a citizen of the United States, residing at Pittsfield, in the county of Berkshire, State 5 of Massachusetts, have invented certain new and useful Improvements in Universal Dies, of which the following is a specification.

My invention relates to dies, and has for its object an arrangement of parts capable 10 of being adjusted to give a stamping of a given form having any desired dimensions.

More especially my invention relates to a universal die and has for its specific object the provision of an arrangement of parts 15 for carrying into effect the method of producing L-shaped punchings, with any given desired dimensions, disclosed in the application for Letters Patent Serial No. 244,431 filed by M. O. Troy on July 11, 1918.

20 In the application above referred to, it has been proposed to have the stock of metal fed to an L-shaped die of fixed dimensions in such a manner that by merely varying the distance along the stock to be fed, the direction of feed, and the proportions on the 25 two sides of the knee of the L, a punching of any desired dimensions may be had.

In accordance with my invention I have provided a die plate, which coöperates with 30 a fixed L-shaped punch, with an independently adjustable stop and guide; thereby controlling the three variable factors determining the dimensions of the punching to be produced by only two independently 35 adjustable elements.

For a more complete understanding of the nature and objects of my invention reference should be had to the following detailed description when taken in connection 40 with the accompanying drawings in which Figure 1 shows in side elevation a coöperating punch and die having my invention applied thereto. Fig. 2 is a plan view of the die plate showing a section of the die taken 45 on line 2—2 in Fig. 1. Fig. 3 is a section taken on the line 3—3 in Fig. 2; and Figs. 4 and 5 show details in section and in elevation respectively.

Referring now to Fig. 1 of the drawing, 50 10 denotes a stationary member, or die plate having therein an L-shaped cavity K bounded by die steels or members 12, 13, 14 and 15 secured about the outer portion of its periphery by screws S as shown in Fig. 2,

to provide the shearing edges, the other or 55 inner edge 16 of the cavity being that of the plain cast metal, such as iron, of which the member 10 is made.

The member 10 has secured therein a number of guide posts 17 adapted to guide 60 the movable member 18 in executing reciprocating movements when driven by any suitable means such as the ram of a punch press.

The member 18 carries the punches 19, 20, 65 21 and 22 (shown in section in Fig. 2) which coöperate with the edges of the die steels 12, 13, 14 and 15 respectively to shear off the punching from the stock as it is advanced under the punches at each successive 70 stroke of the ram. The punches 19 and 22, however, are not engaged in the normal shearing operation but serve chiefly as guides for end portions of the punch.

In addition to the cavity K, the member 75 10 is preferably provided with three or more minor cavities, such as shown at 23, 24 and 25 which serve chiefly as clearance space for securing the exact adjustment of the die steels.

80 As before remarked, the dimensions of the punching sheared off at each stroke of the punch, that is the length and width of each leg of the L-punching, are determined by the distance the stock is advanced at each 85 stroke, the direction of feed and the proportions on each side of the knee of the L-shaped die, which knee is here shown at 26.

Two of these variable factors are controlled by the adjustable guide shown at 30, 90 namely the direction of feed and proportions on each side of the knee 26.

The third of these factors, namely the distance the stock is to be advanced at each stroke of the punch, is taken care of by the 95 stops 31 and 32. It is of course clear that one of these stops is sufficient to take care of this factor in determining the size of the punching to be produced, but it is preferable to provide two of them in order that each leg of the punching may be advanced against a solid abutment during the punching process.

100 The adjustable guide 30 consists of a plate having a groove 33 for the edge of the stock. This plate is swiveled to a post 34 secured to or forming a part of the adjustable base 35. This base 35 is secured by bolts 36 pass-

ing through a slotted portion thereof and engaging in a depressed portion of the stationary member 10. This depressed portion is shown at 48 and is located as much below the level of the plane of the die steels as the post 34 is high so that the groove 33 is operative substantially in the plane of the die steels in guiding the stock to be punched. Secured to the post 34 is the slotted arc member 37 to which the groove-plate of the guide 30 is adjustably secured by the bolt 38 passing through the arcuate slot 39 (see Fig. 2).

It is thus seen that the bolts 36 coöperate with the slot in base 35 to permit the guide 30 to be adjusted across the plane of the die steels to proportion the amount of the stock that is to lie on each side of the knee 26, while the bolt 38 coöperates with slot 39 to 20 accomplish the adjustment of the guide 30 to secure a desired direction of feed.

The stops 31 and 32 are each made in the form of a slotted plate, as shown at 40, whose edge next to the die steels is preferably provided with a reinforcing abutment as shown at 41 in Fig. 3.

The plates 40 are also preferably provided on their underside with splines 42 coöperating with grooves 43 in the member 10 to insure their movement in straight lines to and from the die steels. These stops are secured in adjusted position by means of bolts 44 passing through the slots in the plates 40 to engage with the member 10.

35 Either of the stops 31 or 32 may be adjusted to provide the desired advance of the stock, the other being subsequently adjusted to coöperate at its proper distance from the die.

40 In operation, the stops and guide having been previously adjusted either by calculation or by a cut and try method, the stock to be struck into L-punchings is fed under the punches at each successive upward movement of the punch so that its edge lies in the groove 33 throughout its length at all times. The feeding movement is continued until the stock abuts hard against the abutting edges 41 of the stops 31 and 32, by 45 which time the punch should make its downward movement to shear off an L-punching.

It is true that an L-punching sheared off in this manner may not have the desired shape imparted to the end portions of the 50 legs, but this can readily be taken care of by a separate operation.

While I have here shown an embodiment of my invention which is, at present the best means known to me for carrying the same 60 into effect, I would have it understood that this is merely illustrative and that I do not mean to be limited thereby to the precise details here disclosed since obvious 65 alterations thereof will appear to those skilled in this art, nor in the choice or recog-

nized equivalents except as defined in my claims hereunto annexed.

What I claim as new and desire to secure by Letters Patent of the United States, is:

1. The combination with a relatively 70 movable die and punch having coöperating L-shaped configurations of fixed dimensions, of means for adjusting the distance the stock can be advanced during a stroke, means for adjusting the proportions of the 75 stock on the two sides of the knee of the L, and means for adjusting and controlling the angular direction in which the stock is fed under said punch.

2. The combination with a relatively 80 movable die and punch having coöperating L-shaped configurations of fixed dimensions, of means for adjusting the distance the stock can be advanced during a stroke, and a combined means for adjusting the proportions 85 of the stock on the two sides of the knee of the L and for adjusting the angular direction in which the stock is fed under said punch.

3. The combination with a relatively 90 movable die and punch having coöperating L-shaped configurations of fixed dimensions, of means for adjusting the distance the stock can be advanced during a stroke, and a pivoted guide movable laterally in the plane of the die for both adjusting the proportions 95 of the stock on the two sides of the knee of the L and for adjusting the angular direction in which the stock is fed under the punch.

4. The combination with a relatively 100 movable punch and die having coöperating L-shaped configurations of fixed dimensions, of a base member containing said die, a stop 105 removably secured to said member and movable toward and from a leg of the L, and a swiveled guide having a slotted base secured to said member so as to adjust the proportions of stock on the two sides of the knee of the L and the angular direction of feed to the punch.

5. The combination with a relatively 110 movable punch and die having coöperating L-shaped configurations of fixed dimensions, of a base member containing said die, a stop removably secured to said member and 115 movable toward and from a leg of the L, and a swiveled guide slidably secured to a depressed portion of said member so that said guide turns substantially in the plane of the die.

6. The combination with a relatively 120 movable die and punch of L-shaped configuration whose sides extend beyond the edge of the stock to be punched, of means affording the individual adjustment of three 125 independent degrees of freedom in the feed of said stock.

In witness whereof, I have hereunto set my hand this 28th day of August, 1918.

EDWARD H. BRANSON.
